COMBUSTOR

Robert M. Schirmer and Ellsworth H. Fromm, Bartlesville, Okla., assignors to Phillips Petroleum Company, a corporation of Delaware

Application January 26, 1953, Serial No. 333,047

4 Claims. (Cl. 60—39.23)

This invention relates to combustors. In one of its more specific aspects, it relates to an improved combustor used in a jet engine. In another of its more specific aspects, it relates to a means and a method for regulating the direction of air flow into a prevaporizer type combustion chamber.

One type of aircraft propulsion system, i. e., a turbojet engine comprises an air compressor, fuel inlet means at the compressor outlet, and a gas turbine driven by the combustion products and air, which turbine mechanically drives the said compressor. Thrust is developed by the expansion of the stream of combustion products and unused air through a nozzle or jet in a rearwardly extending direction. One established practice in the art is the introduction of fuel into the combustion chamber in the form of a vapor. The fuel is vaporized in vaporizer tubes which can take any one of several conventional forms. One such type of vaporizer tube is the J-type. Such vaporizer tubes are mounted in the upstream end of the combustor in a tube plate or combustor head and extend into the flame tube or combustor. The tube plate forms a partial closure at the upstream end of the combustor so that primary air from the compressor is directed into the vaporizer tubes located around the peripheral portion of the combustor, and through at least one primary air duct centrally located in the tube plate. The tube plate acts as a director for primary air introduced into the upstream end of the primary combustion zone.

Fuel and air are introduced into the upstream ends of the vaporizer tubes. The vaporizer tubes are exposed to the combustion flames and the fuel is thereby vaporized in the vaporizer tubes. The vaporizer tubes change direction through 180° intermediate their ends so that the vaporized fuel and air mixture formed in the tubes is discharged upstream into the stream of air discharged from the downstream end of the primary air duct. Air flowing through the vaporizer tubes assists in vaporization of the fuel by reducing the partial pressure of the fuel and thus reducing the temperature required for complete fuel vaporization. The air also serves to reduce the deposition of carbon, which results from overheating of the fuel on the walls of the tubes and aids in the transport of any liquid and unvaporized fuel through the vaporizer tubes. This portion of primary air which passes through the vaporizer tubes also aids in obtaining complete combustion of the vaporized fuel discharged from the vaporizer tubes into the primary combustion chamber. The major portion of primary air is introduced through a primary air duct located in the tube plate.

In the operation of such an engine, changes in the regimes of engine operation affect the severity of combustion conditions in the primary combustion zone and have a pronounced influence upon flame stability in the primary combustion chamber. For example, a change in altitude of aircraft from slightly above sea level to 60,000 feet or higher causes as much as a ten fold decrease in density and a corresponding increase in linear velocity of air through the primary air duct. This increased linear

2

air velocity results in an increased penetration of the air into the combustion zone. Such an increase in penetration of air into the combustion zone is detrimental to stable combustion, causing the flame front to move downstream in the combustor. The manner in which the air is supplied to the combustion chamber, as well as the relationship between the quantity of air and fuel, must be regulated in order to maintain stable combustion with widely varying operating conditions.

10 The various objects of this invention will be attained by one or more of the aspects of this invention.

An object of this invention is to provide improved means for regulating the flow of primary air into the primary combustion zone. Another object of the invention is to provide means for limiting the linear velocity of primary air introduced in a downstream direction axially into the primary combustion zone. Another object of the invention is to provide a means for regulating the direction in which air is admitted into the primary combustion zone of a prevaporizer type combustion chamber. Another object of the invention is to provide a means for regulating the direction in which air is admitted into the combustion zone of a prevaporizer type combustion chamber in accordance with the linear velocity of air introduced through the primary air duct. Another object of the invention is to provide a method for regulating the mixing of primary air and vaporized fuel in the combustion zone of a prevaporizer type combustion chamber. Other and further objects of this invention will be apparent to those skilled in the art upon study of the accompanying disclosure and the drawing.

Broadly speaking, this invention comprises a means and method for diverting a portion of primary air, in response to an excess of a predetermined maximum linear air velocity from an axial flow radially into the primary combustion zone. Orifice-type primary air inlets are provided in a poppet valve so as to permit a normal flow of primary air through those inlets into the axial portion of the combustion chamber where the primary air is mixed with prevaporized fuel, preferably introduced in an upstream direction counter to the flow of incoming primary air. An increase in linear air velocity over a predetermined maximum overcomes the force of a spring or biasing force acting on the poppet valve and forces the valve head from its seat at the downstream end of the primary air duct so that air is discharged radially from the primary air duct in addition to flow of primary air through the conduits in the valve head, into the central portion of the combustion zone.

50 Better understanding of this invention will be obtained upon reference to the drawings in which—

Figure 1 is a section elevation of a combustor incorporating the control means of this invention.

Figure 2 is a section view of a modification of the primary air inlet assembly.

Referring particularly to Figure 1 of the drawings, combustor 11 comprises shell 12, open at its downstream end and closed at its upstream end by combustor head 13. Vaporizer tube 14, which is preferably only one of several such vaporizer tubes used in the combustor, is affixed at its upstream end to combustor head 13 and makes a change of direction through 180° intermediate its ends. Air inlet 15 is connected to vaporizer tube 14 through combustor head 13. Fuel inlet conduit 16 extends from a fuel source, not shown, into vaporizer tube 14. Primary air inlet conduit 17 is provided in the central portion of tube plate 13 and the downstream end of conduit 17 forms a valve seat upon which poppet valve 18 is normally seated. Spider member 19 is connected to conduit 17 and supports alignment member 21, alignment member 21 extending beyond the downstream end of conduit 17. Alignment member 21 is provided at its

downstream end with a support member 22. A biasing member, such as spring 23 extends between poppet valve 18 and support member 22. Primary air inlet conduits 24 extend through poppet valve 18 to the central portion of combustor 11 upstream of the outlet end of vaporizer tube 14. Shell 12 is provided, downstream of vaporizer tube 14, with secondary air inlet conduits 25. Combustor 11 is positioned in normal operation within an outer shell which forms with combustor 11 an annular passage for the flow of secondary air from the compressor.

Referring particularly to Figure 2 of the drawings, parts like those described in connection with Figure 1 are designated by like numerals. The primary air inlet in this device is modified by using a biasing means, such as tension spring 23' which is attached to poppet valve 18 and extends upstream therefrom through a portion of the interior of conduit 17. Spring 23' is maintained in fixed position at its upstream end.

In the operation of the device shown in the drawings, fuel and air are introduced into the combustion chamber adjacent the downstream end of conduit 17, wherein the fuel is ignited. Vaporizer tubes 14 are exposed to the burning fuel, whereby the liquid fuel is vaporized. Primary air in addition to that entering the combustor through vaporizer tubes 14 passes through conduit 17 and the plurality of inlet openings 24 in poppet valve 18. The primary air which flows through conduits 24 is admixed with the prevaporized fuel entering the combustion chamber from vaporizer tube 14 and is burned, preferably in the upstream end portion of combustor 11. The tension on spring member 23 or 23' is such that as the linear velocity of air passing through conduits 24 increases to such an extent that the flame front is moved downstream from the inlet end of vaporizer conduit 14, the air pressure overcomes the pressure of spring 23 or 23' causing poppet valve 18 to be displaced from its seat on the downstream end of conduit 17. When poppet valve 18 is displaced, a portion of the air stream passes radially between the downstream end of conduit 17 and poppet valve 18. A portion of the primary air continues to pass centrally into the combustor through inlet conduits 24. By causing a portion of the primary air to pass radially into the combustor upon an increase in linear air velocity above a predetermined maximum, a limit is placed upon the amount of displacement of the flame front downstream which can be caused by an increase in linear velocity of the incoming primary air. The portion of the primary air which is radially introduced into the combustor causes an increase in turbulence in the upstream end portion of combustor 11, thereby resulting in improved combustion in the upstream portion of the combustor.

In the preferred modification of the invention, as shown in Figure 2 of the drawings, tension spring 23' can be used to maintain poppet valve 18 in a normally seated position. In such a modification, alignment member 21 extends through the central portion of poppet valve 18 so as to maintain the poppet valve in alignment with

conduit 17. Tension spring 23' is then affixed to alignment member 21 at a point upstream of poppet valve 18 and is affixed at its downstream end to the upstream side of poppet valve 18. In this construction, the spring member is maintained in an atmosphere of relatively cool incoming primary air and is not subjected to the severe temperature conditions to which spring member 23 is subjected.

Many other modifications of this invention will be apparent to those skilled in the art upon study of the accompanying disclosure. It is believed that such modifications are within the spirit and the scope of this invention.

We claim:

- 15 1. In a combustor having a primary air inlet in its upstream end, the improvement which comprises a poppet valve normally seated at and closing the downstream end portion of said air inlet; air conduits extending through said poppet valve into the axial portion of said combustor; and pressure means biasing said poppet valve against its seat at a predetermined pressure.
- 20 2. An improved combustor which comprises in combination a combustor shell open at its downstream end; a closure member in the upstream end of said shell; at least one vaporizer tube extending from said closure member into the interior of said combustor shell; a primary air inlet extending through said closure member and connected to the upstream end of each said vaporizer tube; a fuel conduit extending into each said vaporizer tube; a primary air inlet conduit extending into each said vaporizer tube; a primary air inlet conduit extending centrally into said vaporizer shell through said closure member; a poppet valve seated at and closing the downstream end of said primary air inlet conduit; inlet conduits extending through said poppet valve and pressure means connected to said poppet valve to bias said valve closed with a predetermined pressure.
- 25 3. The combustor of claim 2 wherein said vaporizer tubes change their direction 180° intermediate their ends and extend to points centrally disposed in the upstream end portion of said combustor, and said pressure means is a tension spring connected to and positioned upstream of said poppet valve.
- 30 4. The combustor of claim 2 wherein said vaporizer tubes change their direction 180° intermediate their ends and extend to points centrally disposed in the upstream end portion of said combustor, and said pressure means is a compression spring positioned downstream of and pressing against said poppet valve.
